UNITED STATES PATENT OFFICE.

HENRY C. ALLEY, OF SINNETT, OKLAHOMA TERRITORY.

TIRE-TIGHTENER.

SPECIFICATION forming part of Letters Patent No. 630,311, dated August 8, 1899.

Application filed June 1, 1899. Serial No. 718,978. (No model.)

To all whom it may concern:

Be it known that I, HENRY C. ALLEY, a citizen of the United States, residing at Sinnott, in the county of Pawnee and Territory of Oklahoma, have invented a new and useful Tire-Tightener, of which the following is a specification.

This invention relates to tire-tighteners, and has for its object to provide improved means whereby the space between the ends of the felly-sections may be adjusted so as to expand the felly and thereby tighten the tire.

To this end the present invention consists in the combination and arrangement of parts, as will be hereinafter more fully described, shown in the accompanying drawings, and particularly pointed out in the appended claims.

In the drawings, Figure 1 is a perspective view of a portion of the rim of a wheel having the present invention applied thereto. Fig. 2 is a longitudinal sectional view of the construction shown in Fig. 1. Fig. 3 is a detail perspective view of one of the cap-plates 25 which is adapted to be fitted to one of the ends of the felly. Fig. 4 is a detail perspective view of the tightening-wedge.

Corresponding parts are designated by like reference characters in all the figures of the drawings.

Referring to the drawings, the invention comprises opposite cap-plates 1 and 2, respectively, which are adapted to be fitted to the adjacent ends of the felly-sections 3 and 4, 35 and a wedge 5, adapted to be driven in between the cap-plates for the purpose of forcing apart the ends of the felly, whereby the latter may be expanded and the tire tightened thereby.

The cap-plates are duplicates in construction, and one of them is shown in detail in Fig. 3. Each cap-plate comprises a substantially rectangular flat head 6, having opposite side flanges 7 and top and bottom flanges 8, forming a socket adapted to receive one of the ends of the felly, whereby the cap-plate is adapted to be fitted thereto. The outer face of the flat head of the cap-plate is corrugated transversely, as shown, so as to facilitate the engagement of the wedge therewith, as will be hereinafter more fully described.

As shown in Fig. 4 of the drawings, the

wedge 5 consists of a longitudinally-tapering plate of a greater length than the width of the felly-sections 3 and 4 and provided upon both sides thereof with longitudinal corrugations or serrations adapted to have an interlocking engagement with the corresponding corrugations or serrations of the cap-plates 1 and 2, between which it is inserted. The said wedge-plate 5 is preferably further provided in one side thereof and intermediate its ends with a transverse incision 9, which permits the projecting portion of the wedge being broken off at the side of the rim after having been forcibly driven between the opposing felly-caps 1 and 2.

In using the invention the cap-plates 1 and 2 are respectively fitted to the opposing ends of the felly-sections 3 and 4, and the wedge-plate 5 is then driven laterally between the said cap-plates from either side of the felly, whereby the longitudinal corrugations or serrations of the wedge will register and interlock with the transverse corrugations or serrations in the outer face of the opposite caps. It will thus be seen that as the wedge is driven in place between the cap-plates the ends of the felly-sections are forced apart by the wedging action, while at the same time the interlocking engagement of the opposing corrugations effectually prevents accidental displacement of the wedge and yet will not interfere with the latter being driven inward or outward, as may be required.

Under some conditions it may be desirable to permanently fasten the wedge in place between the opposite caps 1 and 2, and to secure this result in a simple and effective manner it is only necessary after breaking off the projecting portion of the wedge at the incision 9 to upset or swage the ends of the wedge at the sides of the felly, so as to positively prevent the same from moving in either direction.

Changes in the form, proportion, size, and minor details of construction within the scope of the appended claims may be resorted to without departing from the spirit or sacrificing any of the advantages of this invention.

What I claim is—

1. In a tire-tightener, the combination with opposite ends of an adjacent felly-section, of cap-plates fitted thereto and provided with

transverse corrugations in their outer exposed faces, and a wedge provided with longitudinal corrugations upon opposite sides thereof and adapted to register with the corrugations 5 of the respective cap-plates, substantially as shown and described.

2. In a tire-tightener, the combination with the opposing felly-sections, of the opposite caps fitted respectively to the separate felly-sections and provided with corrugations, a wedge adapted to be inserted laterally between said caps and having corrugations interlocking with those of the latter, substantially as set forth.
- 15 3. In a tire-tightener, the combination with

the felly-sections, of the opposite caps fitted respectively to the separate felly-sections and provided in their outer faces with transverse corrugations, and a wedge-plate adapted to be inserted laterally between said caps and provided with corrugations upon both sides thereof, and in one side with a transverse incision, substantially as set forth. 20

In testimony that I claim the foregoing as my own I have hereto affixed my signature in 25 the presence of two witnesses.

HENRY C. ALLEY.
